Jerry E. Kinsey, St. Louis, Mo.

Application April 10, 1953, Serial No. 24,441

Term of patent 3½ years

(Cl. D57—1)

To all whom it may concern:

Be it known that I, Jerry E. Kinsey, a citizen of the United States, residing in the city of St. Louis and State of Missouri, have invented a new, original, and ornamental Design for an Ornament for Spectacle Frames, of which the following is a specification, reference being had to the accompanying drawing, forming a part thereof.

In the drawing:

Fig. 1 is a front elevational view of an ornament for spectacle frames, showing my new design; and

Fig. 2 is a top plan view thereof.

I claim:

The ornamental design for an ornament for spectacle frames, substantially as shown.

JERRY E. KINSEY.
